UNITED STATES PATENT OFFICE.

GEORGE W. PEASE, OF PITTSFIELD, MASSACHUSETTS.

GARMENT.

1,301,164.

Specification of Letters Patent. Patented Apr. 22, 1919.

Application filed April 5, 1918. Serial No. 226,810.

To all whom it may concern:

Be it known that I, GEORGE W. PEASE, a citizen of the United States, and a resident of Pittsfield, county of Berkshire, and State 5 of Massachusetts, have invented a certain new and useful Garment, of which the following is a specification.

My invention relates to one piece or union garments such as overalls, pajamas or the 10 like, and has for its object to produce such a garment which will give or yield in response to movements of the body of the wearer without unduly straining the garment.

15 A further object is to produce a union garment wherein relative movement of the upper and nether portions is permitted and to provide means whereby dust and dirt will be excluded from within the garment.

20 These and further objects will more fully appear in the following specification and claims and in the accompanying drawings considered together or separately.

I have illustrated one embodiment of my 25 invention in the accompanying drawings in which like parts in all of the several figures are designated by similar reference characters, and in which—

Figure 1 is a back view of a garment embodying my invention.

Fig. 2 is an elevation, on an enlarged scale, of the invention, viewed from the inside of the garment.

Fig. 3 is a section on the line 3—3 of 35 Fig. 2.

Fig. 4 is a section on the line 4—4 of Fig. 2.

Fig. 5 is a view similar to Fig. 2 showing the parts in vertically extended position.

40 Fig. 6 is a section on the line 6—6 of Fig. 5.

Fig. 7 is a view similar to Fig. 2 of a modification.

Fig. 8 is a section on the line 8—8 of 45 Fig. 7.

My invention relates to union garments of the same general type as that shown in a patent issued to me on February 5, 1918, and numbered 1,255,333, which is provided with 50 an opening down the front from the collar to the crotch to permit donning and removal of the garment.

In carrying out my invention I provide a 55 garment comprising a body or upper portion 1 and a trousers or nether portion 2

secured together at the front and back. The waistband 3 extends entirely around the garment and is attached to the body portion 1 for its entire length. The waistband is also attached to the trousers portion 2 except for a short distance at the back thus producing a short slit 4.

A member 5 of a material similar to that of which the garment is composed is secured to the inside of the back of the body portion above the slit 4 by a row of stitching 6 at each side of the member. The stitching 6 extends upward from each side of the slit. The upper part of the member is folded on itself to form a plait or bellows 7, and the top edge of the member is secured to the back of the body 1 by stitching 8. The member 5 may be an integral part of the trousers 2 or it may be a separate piece of material sewed to that portion of the trousers which is not attached to the body portion.

The above mentioned construction produces a pocket formed by the member 5 which is open at the lower side and accessible from the outside of the back of the garment at 80 approximately the waist line. The pocket has a bellows bottom which will permit of downward movement of that part of the trousers portion of the garment which is unattached to the body portion.

When worn and the wearer is in an upright position the garment will be in the position shown in Figs. 1, 2, 3 and 4. The bellows 7 will be stretched across the back in approximately a horizontal line. When the wearer bends over or assumes a sitting position that portion of the trousers portion which is unattached at the waist line will be pulled downward relatively to the body portion and the bellows will be extended as shown in Figs. 5 and 6. This relative movement of the trousers portion will naturally draw the seams 6, 6 at the sides of the member 5 toward the center of the back and will 95 fold the back more or less at the seam 8. When the wearer resumes the upright position the back of the garment will be stretched to straighten out the fold in the back, the seams 6, 6 will be drawn outward to their normal positions thus pulling the bellows to the horizontal line.

The member 5 will cover the slit 4 irrespective of the position of the body of the wearer and the extent to which the slit may 110

be opened, will prevent exposure of the clothing worn under the garment and will close the slit against the entrance of dirt and dust.

5 I may, if desired, attach an elastic suspender 9 to the back of the garment in the vertical center thereof and at a point above the member 5. The lower end of the suspender, when used, is attached to the member 5 above the slit. The suspender will positively return the parts to their normal position after they have been distorted by the movements of the wearer.

10 It will be understood that instead of making the coat and trousers separate and securing them together except for a short distance at the back the body and trousers may be made of a single piece of material, in which event the member 5 or 5^a must be a separate piece sewed on below the slit.

15 The garment will have the appearance of one in which the body and trousers are secured together for the length of the waistband. The back will always present a smooth appearance. There will be no bunches, wrinkles or folds on the outside of the garment to catch in moving machinery. The clothing under the garment will never be exposed, dirt cannot work into the garment to cause injury to the clothing and the garment will have sufficient flexibility to permit it to adjust itself to the body of the wearer and to prevent tearing or ripping caused by movements of the wearer.

20 25 30 35 In accordance with the provisions of the patent statutes I have described the principle of my invention, together with the apparatus which I now consider to represent the best embodiment thereof, but I desire to have it understood that the apparatus shown is merely illustrative, and that the invention may be carried out in other ways.

Having now described my invention what I claim as new and desire to secure by Letters Patent of the United States, is:—

40 45 50 55 60 65 1. A union garment comprising a body portion and a trousers portion permanently secured together at the back and front, there being a portion of the back of the garment at approximately the waist line where the body portion is not attached to the trousers portion, and a member forming part of the trousers portion and extending above the free edge of the body portion, said member being inside of the garment and being attached to the body portion at the upper extremity of the member, said member being provided with a fold or plait above the free edge of the body portion, whereby a portion of said member may be moved relatively to the body portion in the direction longitudinally of the garment.

2. A union garment comprising a body portion and a trousers portion permanently secured together at the back and front,

there being a portion of the back of the garment at approximately the waist line where the body portion is not attached to the trousers portion, and a member forming part of the trousers portion and extending above the free edge of the body portion, said member being inside of the garment and being stitched to the body portion along the upper and side edges of the member, said member being provided with a fold or plait above the free edge of the body portion, whereby a portion of said member may be moved relatively to the body portion in the direction longitudinally of the garment, said fold or plait being located substantially parallel to the free edge of the body portion.

3. A union garment comprising a body portion and a trousers portion permanently united at the back and front, there being a portion of the back of the garment which is unattached, thereby forming a substantially horizontal slit in the back of the garment, and a member attached to the garment at the lower side of the slit, said member being attached to the garment above the slit, there being a plait or fold in the member to permit relative movement of those portions of the garment above and below the slit, the said plait or fold being wholly within the garment.

4. A union garment comprising a body portion and a trousers portion permanently united at the back and front, there being a portion of the back of the garment which is unattached, thereby forming a substantially horizontal slit in the back of the garment, and a member attached to the garment at the lower side of the slit, said member being attached to the garment at a considerable distance above the slit, the member being folded downward and then upward to form a plait or fold in the member to permit relative movement of those portions of the garment above and below the slit, the attaching means retaining the fold or plait in position, the said plait or fold being wholly within the garment and above the slit.

5. A union garment comprising a body portion and a trousers portion permanently secured together at the front and back, a part of the body portion being unattached to the trousers portion thereby forming a slit of less length than the back of the garment at approximately the waist line, a member carried by the trousers portion, said member extending upward inside of the back of the garment and masking the slit, the upper end of the member being folded downward and then upward to form a fold or plait with the upper edge of the member extending above the fold or plait, the upper edge of the member being stitched to the inside of the body portion at a considerable distance above the slit, and substantially parallel thereto, the side edges of the mem-

ber, including the edges of the folded portions, being stitched to the body portion from the level of the slit to the upper edge of the member, the fold or plait being above the slit, and an elastic element attached to the member below the fold or plait and to the body portion above the member.

This specification signed and witnessed this third day of April, 1918.

GEORGE W. PEASE.
